(**) Term: **14 Years**

(57) **CLAIM**

(21) Appl. No.: **29/164,301**

The ornamental design for a multi-purpose watering nozzle,
as shown and described.

(22) Filed: **Jul. 23, 2002**

DESCRIPTION

(51) LOC (7) Cl. **23-01**

FIG. 1 shows a perspective view of the present design.

(52) U.S. Cl. **D23/213**

FIG. 2 shows a front elevational view of the present design.

(58) Field of Search D23/213; 239/459,

239/589, 602

FIG. 3 shows a rear elevational view of the present design.

(56) **References Cited**

FIG. 4 shows a left elevational view of the present design.

U.S. PATENT DOCUMENTS

FIG. 5 shows a right elevational view of the present design.

D415,554 S * 10/1999 Hui-Chen D23/213

FIG. 6 shows a top plan view of the present design; and,

D454,616 S * 3/2002 Hunt D23/213

FIG. 7 shows a bottom plan view of the present design.

D455,815 S * 4/2002 Bonzer D23/213
